Towne Mfg. Co., Stamford, Conn., a corpora-
tion of Connecticut

Application July 8, 1933, Serial No. 679,523

40 Claims. (Cl. 70—77)

This invention relates to a control system and apparatus for protecting currency and valuables in banks or other institutions.

In the bank protecting devices of the prior art, it has been the general principle of operation to create an alarm upon a holdup, so as to summon the police and to warn the entire region surrounding the scene of the holdup. Such devices, while helpful, nevertheless permit access to funds and valuables and make it possible for highwaymen to reach those funds, after which escapes are frequently possible. It is the object of our invention to devise a system which will primarily prevent access to funds, this system being of the type disclosed in the basic application on this subject filed by William Goehring, Serial No. 419,652, and further applied to a drawer locking system by George W. Singleton in application Serial No. 419,590.

In the application of Goehring, there is maintained a group of locks which are normally operative, but which, upon an attack on the bank at any particular place, or upon destruction of any of the circuits which are protected by balanced relays, are individually rendered inoperative so that they can no longer be operated by the usual means. This control functions to maintain the locks inoperative until a definite period, which is arbitrarily set, has elapsed, whereupon the system will once again reestablish itself. One of the features of the Goehring invention in its preferred embodiment, is that the time controlled reset mechanism is itself maintained under supervision of a lock which is part of the general protected lock system. Another, is that the system is reestablished under time control. The system which we are disclosing herein is dominated by claims in the Goehring application, but shows a variation over the Goehring structure whereby to eliminate one of the expensive features of Goehring, that is, the reestablishment of the system by time control. At the same time, however, this invention utilizes the Goehring broad principle of locks rendered inoperative and adapted to be reestablished by means which are themselves under time control.

Specifically, our invention includes a safe mechanism having a locking drawer, a combination locked chest, and a chest which is under time control of the type exercised by a delayed time mechanism shown in the Miller Patent 1,858,964 owned by the assignee of this application. The locking drawer and the regular combination lock of the chest are under the type of

time control disclosed in the Goehring application as will be specifically indicated in this application later, there being an electric circuit which upon the disturbance of any portion thereof, or upon the closing of a push button circuit, will cause the drawer and lock to be rendered inoperative. In order to reestablish the circuit and render the drawer and lock operative again, a control for reestablishing the circuit is located in the chest which is controlled by the delayed time lock device. Therefore, once there is a lockout created, it is necessary to set the delayed time mechanism, the operation of which is described by Miller in his patent, whereupon the time mechanism will run a definite period to permit subsequent opening of the chest whereby to reach the central control mechanism. Naturally, while the drawer, combination locked chest, and time controlled chest are all shown in one structure herein, they may just as well be in separate structures.

Other objects and features of our invention will appear from the description which follows, but the more important features relate to the particular control of the drawer mechanism, the means for deadlocking and maintaining control over the combination lock chest, and the general circuits for controlling the entire arrangement.

For a further description of our invention, we shall now refer to the drawings, wherein Fig. 1 is a view of a safe embodying my invention while Fig. 2 is a view of the same structure showing the combination locked compartment and the time lock compartment opened. Fig. 3 is a wiring representation of the circuit of our mechanism, while Figs 3A and 3B are simplified drawings of a sub circuit for the vigilante alarm, and of the main protection circuit shown in Fig. 3. Figs. 4, 5 and 6 are views of the control mechanism of the combination locked chest. Fig. 7 is a view of the bottom of the drawer in its relation to the remaining mechanism and the housing in which it slides. Fig. 8 is a view similar to Fig. 7 showing the drawer in an open position. Fig. 9 is a view along the lines 3—9 of Fig. 7. Fig. 10 is a view along the lines 10—10 of Fig. 7, while Fig. 11 is a second view of the left hand portion of Fig. 10 with the parts in different relation. Figs. 12 and 13 are views of a portion of Fig. 10 along lines 12—12 enlarged to illustrate the action of the drawer locking mechanism. Fig. 14 is a view along lines 14—14 of Fig. 12, while Fig. 15 is a view taken along the lines 15—15 of Figs. 12. Figs. 16 and 17 are views similar to Figs. 12 and 13 but showing

the relation of the locking drawer to the drawer controlling magnet in the full open position of the drawer. Fig. 18 is a view along the lines 18-18 of Fig. 16. Fig. 19 is a view of the control box apparatus while Fig. 20 is a side elevation of the same.

Referring now to Figs. 1 and 2, reference numeral 10 represents a preferred embodiment of a safe structure in which our invention is incorporated. This safe structure has a lower compartment 11, a middle compartment 12, and an upper drawer compartment 13. It is intended in the ordinary operation of the safe structure, if located in a bank, that the upper drawer compartment 13 shall carry the relatively small amount of money which is necessary for ordinary change. The middle compartment 12 is adapted to carry a reserve amount of currency which is available as soon as the combination lock mechanism 14 is operated by a dial 15 and the bolts 16 retracted by the handle 17. The main amount of currency is to be maintained in the compartment 11 and is only accessible after the combination dial mechanism is set as by the dial 18, and the bolts 19 withdrawn partially by the handle member 20 to start the delayed time lock mechanism 21 as is illustrated more particularly in the Miller patent indicated supra. Once the mechanism 21 is started running as taught by Miller, it is only necessary to wait the delayed period for which the time lock was set, after which the bolts may be withdrawn fully and the compartment 11 rendered accessible.

It is intended in the general operation of our invention, that the drawer 13 be electrically controlled so that upon the depression of the push button 22 it will be possible to move the drawer to an outward position in which it will be allowed to remain. Immediately upon an attack on the bank, the operation of strategically located push buttons, or the upsetting of balanced circuits, etc. will operate controls so that the drawer 13 will be allowed to move to a fully closed position from which position it will be impossible to disturb it until the circuit through the electrical control mechanism of the drawer 13 is restored in a manner which will be set forth later.

The reserve currency which is maintained in the compartment 12 is ordinarily accessible only by the operation of the bolts 16 after setting of the combination mechanism 14 by the dial 15. However, there are located electrical mechanisms, which may be of several types, for preventing the operation of the dial lock 15 in the usual way to retract the bolts 16, immediately upon the disturbance of protection circuits by push buttons or balanced circuits throughout the banking room in the same manner as the circuit through the drawer 13 is disturbed.

In the preferred embodiment of our invention, the compartment 11 is adapted to contain the greater amount of currency carried by the bank or other institution. This compartment is maintained locked by the bolts 19 which are retractable by the handle 20 upon the setting of the combination by the dial 18 and controlled by the delayed time locking mechanism 21. This mechanism is of the type shown in the Miller patent as explained above, in which it is possible to set the time mechanism so that it will operate after 15, 30, 45 or any other number of minutes, to permit the opening of the safe structure, after an initial operation has been carried out. Therefore, should the custodian of the safe

mechanism be forced to set the dial mechanism, the robbers will know quite definitely that it will be impossible to reach the funds in the main structure 11 until the delayed time mechanism has run down. It will be obvious to them that this wait is essential since the fact that the safe is so controlled is to be advertised outside the bank and by conspicuous signs on the safe structure. It will be quite apparent to those skilled in the art that few robbers will be willing to wait 15 or 20 or 30 minutes until the safe structure is open, especially, if incidental to the operation of the locking mechanism for the safe, there is a vigilante or alarm operation.

The invention embodies further the placing of a reset mechanism 23 in the compartment 11 which reset mechanism controls the electrical circuits which prevent the operation of the drawer 13, or the opening of the door of the compartment 12. The reason for locating this mechanism in the chest 11 is to insure that once the circuits through the drawer 13 and through the control of the compartment 12 are broken and access to compartment 12 and the drawer 13 is impossible, that it will be necessary to set up the delayed time lock mechanism 21 and allow the delayed time period to run before the mechanism 23 may be reset to permit access to the compartments 12 and 13. This renders the compartments 12 and 13 robber-resisting since their opening is impossible except after the delayed period of mechanism 21, once an alarm is sent out.

We have now described rather specifically the operation of the devices of Figs. 1 and 2 from a functional viewpoint. We will now indicate more particularly the structural means by which the invention is carried out, although we wish it understood that the general purposes of the invention as set forth with relation to Figs. 1 and 2 may be accomplished by other mechanisms operating on the principle of the mechanisms particularly disclosed herein, and that we feel ourselves entitled to patent claims which will dominate such mechanisms.

Referring now more particularly to Figs. 2, 4, 5 and 6, we show detent mechanism for controlling the operation of the bolts 16 of the door preventing access to the compartment 12. There are mounted on the side surfaces 24 of the compartment 12 a pair of buttress members 25 and 26 which are equipped with portions 27 and 28 for the admission of the upper and lower bolts 16 for the purpose of re-enforcing those bolts in their locking position and for providing a substantial bearing. Behind the surface 24, there is located a plate 29 to which is secured the control mechanism for the bolts 16. This control mechanism includes an electro-magnet 30 having an armature 31 to which is secured a dogging slide 32 mounted slidably on screw threaded studs 33 protruding from the block member 34.

Mounted also on the plate 29 are a pair of switch blade members 35 and 36 insulated from each other and controlled by a spring pressed member 37 which is normally pressed forward in a position to maintain the members 35 and 36 separated as shown in Fig. 4. The cooperative operation of this apparatus will now be explained, but its operation electrically relatively to the entire system will be more specifically shown with reference to Fig. 3 later in this specification. It is intended that the electrical control circuit traversing the electro-magnet 30 shall include

the switch blades 35 and 36 so that it is necessary, in order to complete the circuit through the electro-magnet 38, for the switch members 35 and 36 to be in contact relation as is best shown in Fig. 6. Naturally, the circuit through magnet 38 includes the outside circuit which is controlled by the reset mechanism 23 in the compartment 11, and which, when in a particular condition, will prevent the closing of a circuit through the relay 36 regardless of the position of the switch members 35 and 36. This will prevent the necessary operation of relay 38 as required to obtain access to compartment 12.

As will be quite obvious, should the outside circuit be closed, then retractive movement of the bolts 16 will first cause the upper bolt 16 to contact the spring member 37 to permit switch members 36 and 35 to move into a closed position. This will immediately close fully the circuit through the electro-magnet 38 which will draw the detent member 32 from its position of Fig. 4 to its upper position illustrated in Fig. 6 to permit the lower of the bolts 16 to move into its fully open position of Fig. 6, which movement will be shared by the other two of the bolts 16 as will be quite apparent to those skilled in the art. Access to the compartment 12 is then possible.

We shall now describe the mechanism which controls the operation of the drawer 13. This mechanism is substantially the same in principle of operation as that of the control mechanism of Figs. 4, 5 and 6 and is best illustrated in Figs. 7 to 18 inclusive. Referring now especially to Figs. 7 to 9 inclusive, the drawer 13 has secured to its back plate 59 a regulation liquid checking spring door closer 51 which through its arms 52 and 53 exerts continuous pressure tending to move the drawer 13 into its closed position illustrated in Fig. 7. Upon movement of the drawer to its open position of Fig. 8, the closer will be maintained under tension and adapted to move the drawer to a closed position immediately upon the release of the drawer as will be fully described presently.

For maintaining the drawer in its locked position, and in its open position, and for permitting its movement to open and closed positions, the drawer is equipped with a spring pressed locking tumbler 54 and a triangular locking cam 55 which are in turn cooperable with the armature controlled detent 56 shown best in Figs. 12 to 18 inclusive. This detent member 56 is pivotally mounted on a screw stud 57 and has a dogging portion 58 pivoted at 59 at one of its ends to the armature 60 of the control relay 61. This control relay 61 has external and internal circuits similar to those described in connection with the electro-magnet 38 of Figs. 4, 5 and 6. The relay 61 has an internal circuit comprising the push button 22 and the mercury switch plate 62 which is operated and controlled by the extension 63 secured to the drawer 13 for integral movement therewith. The mercury switch plate 62 has the independent mercury tubes 64 and 65, the operation of which will be more fully described with regard to the electrical control as set forth in Fig. 3.

We will now describe the mechanical operation of the mechanism of Figs. 7 and 8 in detail, with reference to the pawl and locking members 54 and 55 and the detent 56 as controlled by the armature 60 of the relay 61.

Figs. 12, 13, 14 and 15 illustrate more particularly the cooperation of the dog portion 58 of

member 56 with the locking cam member 55 in the position of the locking drawer illustrated in Figs. 7 and 10. As is shown in Fig. 12, when the armature 60 is in its upward position, which is the position it will occupy when the circuit is broken through the relay 61, the cam member 55 will be prevented, by dogging portion 58, from movement to the right, which is the movement it will necessarily have if the drawer is to move to an open position. The drawer will therefore be maintained in a locked closed position. However, should the circuit be established through the electro-magnet 61 by the closing of its internal circuit through push button 22 at the time that its external control circuit is also closed, the armature 60 and dogging portion 58 will be moved downward into the position of Fig. 13 so that the cam member 55 may be moved to the right with the drawer 13 to the open drawer position illustrated in Fig. 8.

In the position of the drawer in Fig. 8, the relationship of the holding tumbler member 54 relatively to the dog 58 is best shown in Figs. 16 to 18 inclusive. As will be quite obvious from Fig. 16, as the drawer moves to an open position with the electro-magnet actuated, as is necessary in order to release the drawer for open movement, the tumbler 54 will be moved downwardly under the dog member 58 against the pressure of its spring 66, and upon reaching the position of Fig. 16 it will jump up into the position illustrated with its end surface 67 solidly against the surface of the dog member 58. In this position, and as long as the electro-magnet 61 is maintained actuated by the closing of its internal and external circuits, the drawer 13 will be held in its open position of Fig. 8. Should the circuit through the electro-magnet 61 be broken, either in its external control circuit in which the mechanism 23 located in compartment 11 is a controlling factor, or in its internal circuit, then the armature 60 will move to its upward position of Fig. 17 whereupon the holding tumbler 54 will pass under the dog 58 and permit the drawer to move to its fully closed and locked position of Figs. 7 and 12.

The internal circuit of the drawer control magnet 61 includes the push button 22 shown mechanically to Figs. 1 and 2, and the mercury tubes 64 and 65 which are controlled by the member 62 secured to the drawer 13. Referring to Figs. 10, 11 and 15, it will be seen that when the drawer is in a fully closed position, the mercury tubes will be inclined in the position best illustrated in Fig. 3, wherein the circuit will be closed through the contacts of the tube 64. However, when the drawer is open, the circuit is then closed through the mercury tube 65. The member 62 is weighted as at 69 so that it will assume the position of Fig. 11 quite readily when released by the outward movement of the rod member 63 of the drawer 13.

The mechanical construction of our control cabinet 23 located in the compartment 11 is best illustrated in Figs. 19 and 20. It includes a series of resistance members 70, 71 and 72 which are variable in type, and electro-magnet 73 which is the main magnet of my control system. This magnet 73 has an armature 74 which carries the pair of switch members 75 and 76 cooperable with switch posts 78 and 79 respectively for a purpose which will be described hereinafter. The spring 75 normally maintains the armature 74 in its position of Figs. 19 and 20 except when the circuit through relay 73 is closed when cir-

cuits will be established at contact points 76, 78 and 77, 79. A reset push button 80 is located on the outer surface of the control cabinet and is adapted to close a circuit at 81 and 82 when moved in a downward resetting direction.

We will now refer to Figs. 3, 3A and 3B which in connection with mechanical constructions already described will more clearly indicate the operation of our invention, and its various functions. Fig. 3 shows a wiring diagram of the entire invention, and will be referred to in describing more particularly the operation of the coil 61 for controlling the drawer, the operation of the mercury tubes 64 and 65 which also function to control the drawer, and the operation of the electro-magnet 30 for controlling the compartment 12 through switch points 35 and 36 operated by the bolt 16 and the switch operating member 37. For describing the operation of the main and supervisory circuit through the coil 73, and the manner of reestablishing this circuit, we will preferably refer to Fig. 3A which illustrates the circuit in a schematic manner, so that its operation is more easily understood than with reference to Fig. 3. Fig. 3B which is similar to Fig. 3A was drawn for the purpose of illustrating schematically the operation of the vigilante or alarm device in the circuit.

In Fig. 3A, normally the main protective circuit through the main alarm relay 73 is closed through contacts 79-77, conductor 85, conductor 86, resistance 78, battery 87, conductor 88, resistance 71, conductor 89 and through the coil 73. In the closed condition of the circuit through the electro-magnet 73, a supervising circuit is established also at switch points 76 and 78 which are shown electrically in Figs. 3 and 3A, and which are shown mechanically in Figs. 19 and 20. This established circuit on one side is from the contact 78 through the conductor 90, the battery 87 to conductor A. On its other side, it is from contact 76 through conductor 91 to main conductor B. The conductors A and B lead to the various drawers and other devices which are to be protected, and which I have shown in this application as embodied in the drawer compartment 13 controlled by the main relay 61, and in the combination lock compartment controlled by the relay 30.

In this closed position of the bank protecting circuit through conductors A and B, there will be maintained a closed external circuit through the coil 30 which controls access to compartment 12. This circuit is shown in Fig. 3 as through the main conductor A, conductor 92, switch points 35 and 36, coil 30 and back to conductor B. In this condition of the circuit through the electro-magnet 30, it will be quite obvious that it will be possible for the operator when retracting the bolts 16, to actuate the member 37 to close the circuit at points 35 and 36 and thus cause the electro-magnet 30 to retract the dogging member 32 and permit full retraction of the bolts 16. This operation is clearly understood when reference is made especially to Figs. 4, 5, and 6. In this condition of the circuit through electro-magnet 30, should an alarm be created in the bank, as by the closing of a circuit at any of the points 93 shown best in Fig. 3A, which may represent push buttons located throughout the bank, the main relay 73 will be immediately short circuited and will not receive the current required to maintain the contacts closed at 77-79 or at 76-78. It is obvious that this short circuit will be through contacts 93,

conductor 86, resistance 78, battery 87 and conductor 88. The opening of the contacts 76-78 will immediately destroy the outside circuit through the relay 73 itself and conductors A and B, which opens the circuit through the relay 30 regardless of the operation of the bolt 16 and the switch members 35 and 36, and it will be impossible to retract dogging detent 32 to obtain access to the compartment 12.

In order to obtain access to compartment 12 eventually, it is, therefore, necessary to reset the circuit as by push button 80 in the control cabinet 23 located in the compartment 11. To do this it is required to set up the combination 18, retract the bolts 19 of the compartment 11, start the running of the delayed time movement 21 so that after the predetermined period of time for which this movement is set, it will be possible to reach into the compartment 11 and to operate the push button 80. The operation of this push button is best described and shown with reference to Fig. 3A in which it is quite obvious that a circuit will be closed at contacts 82, 81, conductor 94, conductor 85, conductor 88, resistance 78, battery 87, conductor 89, resistance 71, conductor 89, through the coil 73, and back through conductor 95 to the contact 82.

Obviously, this operation will have reestablished the circuit once more through the contacts 77, 79 and 76, 78 respectively by the attraction of the armature member 74 against its spring 75 so that the circuit of relay 73 is closed and the supervisory circuit is once more closed through the conductors A and B and therefore through the outside circuit of the electro-magnet 30.

Naturally, in so far as the control by relay 73 of the circuits through contacts 77-79 and 76-78 is concerned, it is immaterial what type of structure is to be controlled, and how that structure is to be controlled through internal circuits dependent on the main supervisory circuit. Thus, the control by relay 73 is the same for the drawer 13 as for the compartment 12 which has just been described. Also, the resetting of the circuit through the relay 73 is entirely independent of the other circuits which the relay may control. I shall now describe more particularly the local or internal circuit of the drawer 13 whereby it is permitted to open and close while controlled externally by the electro-magnet 73 similarly to the control exercised over chest 12.

Under normal conditions, the external circuit through the drawer relay 61 will always be closed so that the operation of the relay under normal conditions will be entirely dependent on the operation of the drawer internal circuit comprising the push button 22 and the mercury tubes 64 and 65 which move as the drawer is operated into open and closed positions. In Fig. 3 and in Figs. 10 and 12, the drawer is illustrated in its closed position and with the circuit as naturally conditioned in that position. With the push button contact 103 against the contact 102 and with the mercury tube 65 in its particular position with the mercury down at its lower end so that the contacts are open at point 83, there is no circuit through the coil 61, contact 103, contact 102, conductor 104, open contacts 83 and 70 back to conductor A. It will now be impossible to open the drawer.

However, should the push button 22 be moved to close the circuit between contacts 103 and 105, a circuit will be established through con-

ductor B, conductor 101, coil 61, contacts 103 and 105, conductor 106, contacts 84 of tube 64, and conductor A. It will then be possible to move the drawer to an open position since the 5 electro-magnet 61 will have acted to withdraw the dog member 58 out of the path of the locking cam 55 as shown mechanically in Fig. 13. As soon as the drawer has moved from the position of Fig. 10 to the open position of Fig. 11, the 10 weighted portion 69 of the mercury tube carrying arm 62 permits the movement of the tube to the position of Fig. 11 wherein the circuit will be broken at control points 84 of tube 64 and will be established at contact points 83 of 15 the tube 65. This is done so that as soon as the drawer has moved outwardly somewhat, release of the push button to separate the contacts 102 and 105 will still permit the circuit to remain closed through the electro-magnet 61 so that the 20 dog 58 will be able to cooperate with the spring pressed pawl member 54 in the position of Fig. 16 for maintaining the drawer in an open position. The circuit so established by the outward movement of the drawer accompanied by the 25 release of button 22 to the position in Fig. 3 is as follows: Conductors B and 101, coil 61, contacts 103 and 102, conductor 104, contacts 83 and conductor A.

In this position of the parts which is illustrated 30 mechanically in Fig. 16, it is quite obvious that the circuit through the electro-magnet 61 may be easily broken by the movement of the push button 22 to reestablish the circuit through contacts 103 and 105 which will break the circuit 35 through contacts 102 and 103 permitting the armature 60 of the electro-magnet 61 to assume its position of Fig. 17 so that the drawer will be allowed to close and assume its original locked position of Fig. 12. It is also possible in the 40 position of the parts in Fig. 16, for any one of the push buttons 93 in the external circuit to be closed so that the main relay magnet 73 will break the external supervisory circuit through the electro-magnet 61 and thus disable the 45 drawer, permitting it to be closed by closer 51 and to remain closed until the main relay circuit is reestablished by the push button 88 of the control cabinet 23 located in the compartment 11 controlled by the delayed time mechanism.

50 Naturally, additional mechanisms may be placed under the control of the main relay 73 as shown in Fig. 3. Also a vigilante or alarm may be placed into the circuit as at 107 to be set into operation immediately upon the closing 55 of one of the alarm buttons 93 operable to throw off the relay 73. Preferably the alarm is operable by a predetermined increase in current therethrough or by a decrease as might be caused by the cutting of its external wires.

60 The electrical operation of the vigilante 107 or alarm member 107, is shown in Figs. 3 and 3A, but is best illustrated schematically in Fig. 3B, to which reference will now be made. Ordinarily, in the regular conditioning of the circuit, 65 there will be a circuit established from the battery 87 through resistance 71, through the relay 73 and the resistance 72 in parallel, and then through the vigilante 107 and the resistance 70 in parallel and back to the other side of the 70 battery 87. The electricity thus traversing the circuit and vigilante 107 is not sufficient to positively actuate it, it being sufficient, however, for the proper actuation of the control relay 73. In case of an alarm, a circuit is closed at 93 75 which immediately short circuits resistances 71

and 72 and control relay 73, so that a circuit is now established through the battery 83, contacts 93, and then through resistance 70 and vigilante 107 in parallel, and back to the other side of the battery 87.

The current now traversing the vigilante 107 is of such considerable strength as to operate the vigilante and excite the alarm. As soon as the circuit is broken at points 93, the vigilante 107 will no longer operate and the circuit will 10 be as follows: From the battery through resistances 71, 72 in series, and then through the resistance 70 and the vigilante 107 in parallel and back to the other side of the battery. The resistances 71 and 72 are now in series with the 15 vigilante 107 and there will obviously not be sufficient current for the vigilante to operate. When the button 88 is depressed so as to establish a circuit at 81—82 there will be a closing 20 of the circuit through the main relay 73 so as to reestablish the circuit into its original condition. Resistance 70 is required not only to adjust the circuit through alarm 107, but to allow functioning of the electrical circuit in case the wires leading to alarm 107 are cut. 25

An additional feature is the button 188 located in compartment 12 and which is positioned in the electrical circuit as shown in Fig. 3. This button is used to break the outside circuit through the relay 61 so that it will be impossible 30 to open the drawer 13 unless one knows the combination of lock 14 so that the custodian of the drawer 13 may feel free to leave the same at any time without destroying the circuit through the other protected devices. 35

While we have thus shown a particular modification of our invention, and a preferred manner of operating the same, it should be understood that we consider this invention to be of relatively broad scope and that we feel ourselves 40 entitled to a broad interpretation of the claims appended hereto.

We claim:

1. In a money protecting system of the class described, a money containing compartment, an 45 electrical control circuit for said compartment, and manually operated control means for said circuit located in a compartment to which access for manual operation is time controlled.

2. In a money protecting system of the class 50 described, a money containing compartment, an electrical control circuit for said compartment to control opening thereof, a manually operated control device for said circuit, said device being located in a second compartment and means 55 whereby access to said second compartment for manual operation of said device is controlled by time mechanism.

3. In a money protecting system of the class described, a money containing compartment, an 60 electrical control circuit for said compartment to control opening thereof, a manually operated control device for said circuit, a further compartment in which said control device is located against manual manipulation, and time controlled mechanism for delaying access to said control device.

4. In a money protecting system of the class described, an electrical control circuit for said compartment to control opening thereof, a 70 manually operable control device for said circuit, a further compartment in which said control device is located against manual manipulation, and a delayed time mechanism for said further compartment to prevent access to said control means 75

until a definite period after the delayed time mechanism has been started.

5. In a money protecting system of the class described, a money containing compartment, an electrical circuit for said compartment for controlling access thereto, the control exercised by said circuit being dependent upon its condition, means for conditioning said circuit to prevent access to said compartment, means manually operable for conditioning said circuit to permit access to said compartment after said circuit has been conditioned to prevent access, said means being located in a second compartment to which access is time controlled.

15. 6. In a money protecting system of the class described, a money containing compartment, an electrical circuit for said compartment for controlling access thereto, the control exercised by said circuit being dependent upon its conditions, means for conditioning said circuit to prevent access to said compartment, means manually operable for conditioning said circuit to permit access to said compartment after said circuit has been conditioned to prevent access, and time controlled mechanism for delaying access to said means.

30. 7. In a money protecting system of the class described, a money containing compartment, an electrical circuit for said compartment for controlling access thereto, the control exercised by said circuit being dependent upon its condition, means for conditioning said circuit to prevent access to said compartment, means for conditioning said circuit to permit access to said compartment after said circuit has been conditioned to prevent access, and a delayed time mechanism for preventing access to said means until a definite period after the time mechanism is started running.

40. 8. In a money protecting system of the class described, a money containing compartment, an electrical circuit for said compartment for controlling access thereto, said circuit having internal and external portions, control means in said internal portion for governing opening and closing of said compartment, said external portion having means conditioned upon attack whereby to prevent access to said compartment, said means being located in a compartment to which access is time locked.

50. 9. In a money protecting system of the class described, a money containing compartment, an electrical circuit for said compartment for controlling access thereto, said circuit having internal and external portions, control means in said internal portion for governing opening and closing of said compartment, said external portion having means conditioned upon attack whereby to prevent access to said compartment, means for conditioning said circuit after attack to permit access to said compartment, and time controlled mechanism for delaying access to said means.

60. 10. In a money protecting system of the class described, a money containing compartment, an electrical circuit for said compartment for controlling access thereto, said circuit having internal and external portions, control means in said internal portion for governing opening and closing of said compartment, said external portion having means conditioned upon attack whereby to prevent access to said compartment, means manually operable for conditioning said circuit after attack to permit access to said compartment, and delayed time mechanism for said

compartment to prevent access to said manually operated means until the expiration of a definite period after the time mechanism is started running.

11. In a money protecting system of the class described, a money containing compartment, an electrical circuit for said compartment for controlling access thereto, said circuit having internal and external portions, control means in said internal portion for governing opening and closing of said compartment, said external portion having means conditioned upon attack whereby to prevent access to said compartment regardless of the operation of the internal portion of said circuit, means for manually conditioning said circuit after attack to permit access to said compartment, said means being located in a compartment to which access is time controlled.

15. 12. In a money protecting system of the class described, a money containing compartment, an electrical circuit for said compartment for controlling access thereto, said circuit having internal and external portions, control means in said internal portion for governing opening and closing of said compartment, said external portion having means conditioned upon attack whereby to prevent access to said compartment regardless of the operation of the internal portion of said circuit, means for manually conditioning said circuit after attack to permit access to said compartment, and time controlled mechanism for delaying access to said means.

20. 13. In a money protecting system of the class described, a money containing compartment, an electrical circuit for said compartment for controlling access thereto, said circuit having internal and external portions, control means in said internal portion for governing opening and closing of said compartment, said external portion having means conditioned upon attack whereby to prevent access to said compartment, regardless of the operation of the internal portion of said circuit, means for manually conditioning said circuit after attack to permit access to said compartment, said means being located in a compartment to which access is time controlled, and delayed time mechanism for said compartment to prevent access to said means until the expiration of a definite period after the time mechanism is started running.

25. 14. In a money protecting system of the class described, a drawer, spring pressed means arranged to move said drawer to closed position, a single electromagnetic controlled detent for controlling said drawer, and means on said drawer cooperable with said detent for maintaining said drawer locked, and for maintaining said drawer open against the pressure exerted by said spring pressed means.

30. 15. In a money protecting system of the class described, a drawer, an electromagnetically controlled detent for controlling the operation of said drawer, means on said drawer cooperable with said detent for maintaining said drawer locked in a closed position, an additional means cooperable with said detent for locking said drawer in its open position, an electric circuit for said electromagnetically controlled detent, proper conditioning of said circuit being effective to actuate the detent to release said drawer for movement to open position, or for movement to closed position, and means for moving said drawer to closed position when said circuit is closed with said drawer in its open position.

35. 16. In a money protecting system of the class

described, a drawer, an electromagnetic drawer controlling detent, means on said drawer cooperable with said detent in the closed position of the drawer for maintaining said drawer locked, 5 additional means on said drawer cooperable with said detent in the open position of the drawer for locking the drawer in its open position, said detent being operable by proper conditioning of an electromagnetic circuit therethrough to permit 10 opening of the drawer from its closed position and closing of the drawer from its open position, readily accessible means operable to condition said circuit to release the drawer for opening and closing movement, and means accessible only after the expiration of a delayed period for conditioning said circuit independently of said first means.

17. In a money protecting system of the class described, a drawer, an electromagnetic drawer controlling detent, a circuit for the electromagnet of said detent, a switch on the outside of said drawer operable to permit proper opening and closing of said drawer, said circuit extending outside of said drawer, attack circuits for controlling said outside circuit, means for resetting said outside circuit, and delayed time mechanism for preventing immediate access to said means.

18. In a money protecting system of the class described, a drawer, an electromagnetic drawer controlling detent, a circuit for the electromagnet of said detent, a switch on the outside of the drawer for controlling said circuit and detent, and a second switch mechanism in said circuit operated by movement of the drawer.

19. In a money protecting system of the class described, a drawer, an electromagnetic drawer controlling detent, an electric circuit for the electromagnet of said detent, a locking dog secured to said drawer and obstructed by said detent in one of its positions to prevent movement of the drawer to open position, said detent being movable to a second position to permit movement of said locking dog and drawer to open position, a further dog on said drawer cooperable with 45 the detent in said second position to maintain the drawer open, said detent being movable to its initial position to permit the drawer to close and to lock the drawer in said closed position.

20. In a money protecting system, a main relay, a protective circuit supervised by the condition of the relay, a conditioning circuit for said relay adapted to be opened upon alarm to render said relay inoperative, and a second circuit through said relay adapted to be closed to 50 excite said relay after it has been rendered inoperative, means for closing said second circuit to excite said relay, and time controlled means for delaying access to said means.

21. In a money protecting system, a main relay, a protective circuit supervised by the condition of the relay, a conditioning circuit for said relay adapted to be opened upon alarm to render said relay inoperative, a second circuit through said relay adapted to be closed to excite said 55 relay after it has been rendered inoperative, and control means for said second circuit maintained under time control.

22. In a money protecting system of the class described, a money containing compartment, 60 electro-magnetic controlled means for locking said compartment, an electric control circuit for said electromagnetically controlled means adapted to be variously conditioned for the purpose of controlling the locking and unlocking of 65 said compartment by said electromagnetically

controlled means, a central control switch for said circuit, said circuit being so arranged that it may only be properly conditioned to permit access to said compartment when said central control switch is operated in a predetermined means, a housing for said control switch, and a time movement of the delayed operation type adapted to delay access to said housing.

23. In a money protecting system of the class described, a drawer, electro-magnetic means for maintaining said drawer locked, a circuit for said means having a switch on the outside of said drawer, said electro-magnetic means being operable to release said drawer to permit its movement to open position when said switch is operated, means whereby said circuit electro-magnetic means maintains said drawer in open position, said means being arranged to permit the door to move to a closed position upon a second actuation of said circuit switch.

24. In a money protecting system of the class described, a drawer, an electro-magnetic detent, a locking member cooperable with said drawer and detent for maintaining the drawer locked, said detent being arranged to release the locking member to permit the opening of the drawer upon a proper conditioning of the electric circuit through said magnet, locking means cooperable with said detent and drawer to maintain the drawer in an open position, said locking means and drawer being releasable upon further conditioning of the circuit of said electro-magnetic detent to permit closing of the drawer, and means whereby an integral portion of the circuit of said electromagnetic detent is maintained under delayed time control.

25. In a money protecting system, a money containing compartment, electrically controlled means for locking said compartment, an electric circuit for said means, a control means for said electric circuit, a second compartment in which said control means is housed, delayed time controlled locking means for said second compartment for delaying access to said control means, means whereby said electric circuit may be conditioned so that said electrically controlled means will maintain said first compartment locked, said circuit being adapted for reconditioning by said control means, whereby said electrically controlled means will unlock said compartment, said control means being accessible only after the expiration of a predetermined interval after the starting of the time operation of said time controlled means for said second compartment.

26. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position, and adapted also to maintain its own circuit closed, and means for breaking, in effect, the supervisory circuit through said relay so as to reverse the said condition of the electric circuit and to simultaneously open its own circuit.

27. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position.

- and adapted also to maintain its own circuit closed, means for breaking, in effect, the supervisory circuit through said relay so as to reverse the condition of the electric circuit and to simultaneously open said supervisory circuit, and means under time control for once again closing in effect said supervisory circuit to energize the relay. 5
28. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position and adapted also to maintain its own circuit closed, means for breaking, in effect, the supervisory circuit through said relay so as to reverse the condition of the electric circuit and to simultaneously open said supervisory circuit, means for closing, in effect, the said supervisory circuit through the relay, and time controlled means for delaying the operation of said means. 10
29. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position and adapted also to maintain its own circuit closed, means for breaking, in effect, the supervisory circuit through said relay so as to reverse the condition of the electric circuit and to simultaneously open said supervisory circuit, means for closing, in effect, the said supervisory circuit through the relay, and a delayed time device for preventing access to said means until the expiration of a predetermined time interval. 15
30. In a money protecting system, a money containing compartment, electrically controlled means for locking said compartment, an electric circuit for said means adapted when closed to maintain said means in unlocking position, a relay, a circuit for said relay, means controlled by said relay when its circuit is closed for maintaining its circuit closed thereafter and for maintaining said electric circuit closed, means for breaking, in effect, the circuit of said relay whereby to open its own circuit and said electric circuit to lock said compartment. 20
31. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position, means for breaking, in effect, the supervisory circuit through said relay so as to reverse the said condition of the electric circuit, means for remaking the circuit, and delayed time mechanism for delaying access to said means. 25
32. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position, means for breaking, in effect, the supervisory circuit through said relay so as to reverse the condition of the electric circuit and to simultaneously open said supervisory circuit, and means under time control for once again closing in effect said supervisory circuit to energize the relay. 30
33. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position, means for breaking, in effect, the supervisory circuit through said relay so as to reverse the condition of the electric circuit, means for closing, in effect, the said supervisory circuit through the relay, and time controlled means for delaying the operation of said means. 35
34. In a money protecting system, a money containing compartment, electrically controlled means for locking said compartment, an electric circuit for said means, a supervisory circuit for said electric circuit, a relay in said supervisory circuit adapted when energized to maintain said electric circuit so conditioned that said locking means will be movable into unlocking position, means for breaking, in effect, the supervisory circuit through the relay, and a delayed time device for preventing access to said means until the expiration of a predetermined time interval. 40
35. In a money protecting system, a money containing compartment, electrically controlled means for locking said compartment, an electric circuit for said means adapted when closed to maintain said means in unlocking position, a relay, a circuit for said relay, means controlled by said relay when its circuit is closed for maintaining its circuit closed thereafter and for maintaining said electric circuit closed, means for breaking, in effect, the circuit of said relay whereby to open its own circuit and said electric circuit to lock said compartment, and time controlled means for remaking said relay circuit. 45
36. In a money protecting system, a drawer, means normally maintaining said drawer in an open position, means for releasing said drawer so that it may move to a fully closed position, means for moving said drawer to said fully closed position upon its said release, means for locking said drawer in its fully closed position, and delayed time controlled mechanism for preventing manual manipulation of said drawer locking means to open said drawer until the expiration of a predetermined period of time. 50
37. In a money protecting system, a drawer, means normally maintaining said drawer in an open position, electrically operated means for releasing said drawer so that it may move to a fully closed position, means for moving said drawer to said fully closed position upon its said release, means for locking said drawer in its fully closed position, and delayed time controlled mechanism for preventing manual manipulation of said drawer locking means to open said drawer until the expiration of a predetermined period of time. 55
38. In a money protecting system, a drawer, means normally maintaining said drawer in an open position, means for releasing said drawer so that it may move to a fully closed position, means for moving said drawer to said fully closed position upon its said release, means for locking 60
- means for breaking, in effect, the supervisory circuit through said relay so as to reverse the condition of the electric circuit and to simultaneously open said supervisory circuit, and means under time control for once again closing in effect said supervisory circuit to energize the relay. 65
- 75

- said drawer in its fully closed position, an electric circuit having means for releasing said locking means when said circuit is properly conditioned, means for so conditioning said circuit, and time controlled mechanism whereby said conditioning means are normally maintained inaccessible and are rendered accessible only after the expiration of a predetermined period of time delay.
39. In a money protecting system, a drawer, an electrically controlled means for maintaining said drawer open, means whereby said electrically controlled means are actuatable to release said drawer for closing movement, electrically controlled means for locking said drawer in its closed position, an electric circuit for said electrically controlled means, means whereby said circuit is conditioned to actuate said electrically controlled means to release said drawer, a com-

partment in which said last mentioned means is located, and a delayed time lock for delaying access to said compartment.

40. In combination; a control-cabinet provided with a closure; a time-control lock for said closure; a drawer and locker unit comprising a locker provided with a lock-equipped closure and a drawer equipped with drawer-closing and locking means; and an electric circuit system controlling the closing and locking of said drawer and the unlocking of the drawer and the locker-closure, said electric system including means outside said control-cabinet for initiating the closing and locking of said drawer and including also a relay system housed in said control-cabinet having a re-set switch operable only after gaining access to the interior of said control-cabinet.
